ABSTRACT: A pair of interconnected sylphon bellows or the like and a control valve adjustable to regulate discharge from the common passageway interconnecting the bellows, which discharge may be connected through a discharge line to actuate a device or pump up a container.

BELLOWS EXERCISER AND PUMP

BACKGROUND OF THE INVENTION

This invention pertains to an exerciser and pumping device, and is particularly directed to a pair of squeezable bellows connected to a common passageway in which is provided a regulatable discharge valve for converting the device from an exerciser to a pump.

Heretofore, squeezable exerciser devices were limited to just certain exercising movements and had no capability of also using the device to do useful work while also being used in providing exercise. Further, prior devices could not be quickly converted from one type of use to another by the simple adjustment of a regulating and control valve associated with the device.

SUMMARY OF THE INVENTION

One of the objects of this invention is to provide an exerciser device which functions at one time as a bellows exerciser and at another time as a pump.

A further object is to provide a device which can be converted from exercising function to pump function by the simple adjustment of a control valve of the unit.

And a still further object is to provide a bellows exerciser device having a pair of bellows arranged so that when squeezed alternately by the hands opposed manual manipulation exercise results and when the bellows are squeezed simultaneously, the device functions as a pump.

BRIEF DESCRIPTION OF THE DRAWINGS

FIG. 1 is an outside plan view of the combined exerciser and pump incorporating the features of this invention.

FIG. 2 is an enlarged fragmentary sectional view of the apparatus shown in FIG. 1.

FIG. 3 is an enlarged fragmentary sectional view on the line 3-3 of FIG. 2.

DESCRIPTION OF THE PREFERRED EMBODIMENT

The bellows exerciser and pump of this invention comprises a central tubular body 10 having outer diameter portions 11 and 12 to which are connected the necks 13 and 14 of the bellows 15 and 16 forming a sealed rigid connection with the body 10. The ends of the body 10 have recessed passageways 17 and 18, both of which open into the bellows interior chambers 19 and 20 and communicates through ports 21 and 22 with the common valve chambers 23 formed within a central partition 23 a in the body 10. A discharge pipe 24 is threaded mounted at 25 in the body 10 and has a passageway 26 communicating with the common valve chamber 23. A suitable discharge hose 27 may be connected to the outer tapered end 28 of the discharge pipe 24.

A rotatable valve stem 29 having a thumb knob 30 is threaded mounted in the body 10 and has a tapered inner end 32 arranged to engage the valve seat 33 formed by the

upper end of the passageway 26. A passageway 34 in the valve stem 29 has ports 35 in communication with the common valve chamber 23. A check valve plunger 36 has a tapered upper end 37 which engages the valve seat 38 of the valve seat bushing 39 appropriately fixed in the counterbore 40 of the thumb knob 30 of the valve stem 29. A compression spring 41 within the valve stem 29 normally yieldingly urges the check valve plunger 36 against the seat 38.

10

OPERATION

When the valve stem 29 is screwed inwardly by knob 30 to seat its tapered end 32 on the discharge valve seat 33, air is confined within the bellows chambers 19 and 20, and the passageways 17 and 18, ports 21 and 22, and 35; and chamber 23. The check valve is normally closed at this time and only lets in air to maintain the described areas fully charged. Under these conditions it is utilized as an exerciser by alternately squeezing one or the other bellows 15 and 16 between the palms 42 and forefingers 43 of the hands, the air shuttling back and forth between the bellows chambers 19 and 20.

To utilize the device as a pump to discharge air under pressure out through the hose 27, the valve plunger 36 is screwed outwardly so as to open the common valve chamber 23 to communication with the passageway 26. Both bellows 15 and 16 are squeezed and released simultaneously to discharge air pressure through the hose 27 and then take in air through the relief check valve 36.

I claim:

1. A bellows exerciser and pump comprising:
  - A. a body,
  - B. a pair of bellows having chambers therein mounted on the body,
  - C. a passageway in the body in communication with the bellows chambers,
  - D. an adjustable valve in the body for connecting the passageway to outside atmosphere or to shut off such connection,
  - E. and a check valve in the body limiting flow from atmosphere only into the body passageway which automatically prevents outward flow to atmosphere from the passageway,
  - F. said adjustable valve comprising a valve stem one end of which engages a valve seat in a port in the passageway leading into a discharge pipe of the body,
  - G. said check valve being arranged in said valve stem at another end for providing an air intake port into said passageway.
2. The bellows exerciser and pump of claim 1 wherein said adjustable valve is threaded connected to the body and which upon rotation closes the passageway in communication with the bellows chambers and opens the port in the passageway leading into the discharged pipe of the body.
3. The bellows exerciser and pump of claim 1 wherein said valve stem has a tapered inner end engaging a valve seat in a port in the passageway leading into a discharge pipe of the body.
